(57) **CLAIM**

We claim the ornamental design for an exercise bike fan, as shown and described.

DESCRIPTION

FIG. 1 shows a top front isometric view of an exercise bike fan in accordance with the present design.

FIG. 2 shows a front elevation view of the exercise bike fan of FIG. 1.

FIG. 3 shows a rear elevation view of the exercise bike fan of FIG. 1.

FIG. 4 shows a left side elevation view of the exercise bike fan of FIG. 1.

FIG. 5 shows a right side elevation view of the exercise bike fan of FIG. 1.

FIG. 6 shows a top plan view of the exercise bike fan of FIG. 1; and,

FIG. 7 shows a bottom plan view of the exercise bike fan of FIG. 1.

The broken lines illustrate portions of the exercise bike fan that form no part of the claimed design.

1 Claim, 5 Drawing Sheets
